UNITED STATES PATENT OFFICE.

KARL VÖLLER, OF DUSSELDORF, GERMANY.

GUN FIRING AT HIGH ELEVATIONS.

1,413,077.

Specification of Letters Patent. Patented Apr. 18, 1922.

Application filed August 18, 1914. Serial No. 857,347.

(GRANTED UNDER THE PROVISIONS OF THE ACT OF MARCH 3, 1921, 41 STAT. L., 1313.)

To all whom it may concern:

Be it known that I, KARL VÖLLER, engineer, a subject of the German Emperor, residing at Dusseldorf, 12 Scharnhorstrasse, 5 Germany, have invented certain new and useful Improvements in Guns Firing at High Elevations; and I do hereby declare the following to be a full, clear, and exact description of the invention, such as will 10 enable others skilled in the art to which it appertains to make and use the same.

Guns firing at a high elevation are known in which a device, liberated when the gun barrel is brought from the firing position 15 into the loading position, locks the trigger until the latter is unlocked by the return of the barrel into the elevated firing position. The device consists of a two-armed lever mounted to turn on the gun carriage and 20 adapted to hold with one of its ends a spring pin, which locks the trigger while its other end bears against a stop which is carried on a part of the elevating mechanism that remains stationary during the return from 25 the elevated position.

This invention relates to a construction of this device which is improved in respect of the fact that security against premature firing of the gun also obtains when the gun 30 barrel has not returned completely into its original position. For this purpose the arm of the lever is permanently connected with an eye carried by the lower end of the locking pin.

35 A construction according to the invention is shown in Fig. 1 of the accompanying drawing in side elevation. Fig. 2 is a section on line 2—2 of Fig. 1. Fig. 3 shows the engagement between the locking pin and 40 the trigger lever.

On the gun carriage is journalled a two-armed lever *u* one end of which bears upon a lug *v* on a part of the elevating mechanism which remains stationary during the 45 return of the barrel from the elevated or firing position to the loading position. A locking pin *w*, mounted in a housing on the gun barrel is designed, in the charging position, which is that shown in the drawing, to 50 prevent movement of the trigger lever *y* in the direction for firing. The lever *u* is subject to the action of a spring *z* which continually tends to bring the lever into the safety

position. So also the spring *s* urges the locking pin *w* into the safety position. 55

Assuming that the gun barrel, together with the gun carriage and the toothed segment *f* of the elevating mechanism, is in the elevated position and is now to be charged, the coupling *i* is disengaged in the known 60 manner with aid of the hand lever *q* and connecting rod *o*, and then the carriage together with the barrel is swung back into the horizontal position while the toothed segment *f* retains the position which it had. 65 In consequence the end of the lever *u* is disengaged from the lug *v* and the springs *s* and *z* bring the locking pin *w* into the safety position shown in Fig. 3. It is therefore now impossible to move the trigger and to 70 fire the gun prematurely.

Only after the gun has been charged, the breech has been closed and the gun barrel has been depressed again at its rear end, whereby the coupling *i* has become again 75 engaged, is the lever *u* moved by the lug *v* against the action of the spring *z* and *s*; this lever now withdraws the locking pin *w* from the safety position so that the gun can 80 be fired in the properly elevated position.

Owing to the continual engagement of the lever *u* in the eye *w'* of the locking pin, such engagement and the action of the parts is ensured even if the gun barrel is not returned into its original position after firing. 85

I claim as my invention:

The combination with a gun for firing at high elevations, a cradle for said gun, and an elevating mechanism, of a trigger lock on said gun having an eye at one end, a 90 lever fulcrumed on said gun cradle for moving said lock, one arm of said lever having a sliding engagement with the eye of said lock, and a projection on a part of said elevating mechanism with which the other arm 95 of said lever is designed to contact to effect retraction of said locking pin when the gun is returned to its firing position.

In testimony whereof, I have signed this specification in the presence of two subscribing 100 witnesses.

KARL VÖLLER.
